UNITED STATES PATENT OFFICE.

ALBERT PATITZ, OF MERIDEN, CONNECTICUT, ASSIGNOR TO THE BRADLEY & IFUBBARD MANUFACTURING COMPANY, OF SAME PLACE.

DESIGN FOR A HARP FOR HANGING LAMPS.

SPECIFICATION forming part of Design No. 17,876, dated November 8, 1887.

Application filed September 26, 1887. Serial No. 250,788. Term of patent 7 years.

To all whom it may concern:

Be it known that I, ALBERT PATITZ, of Meriden, in the county of New Haven and State of Connecticut, have invented a new Design for 5 a Harp for Hanging Lamps; and I do hereby declare the following, when taken in connection with accompanying drawing and the letters of reference marked thereon, to be a full, clear, and exact description of the same, and which 10 said drawing constitutes part of this specification, and represents a face view.

This invention relates to a design for that portion of a hanging lamp which forms the frame to carry the lamp-fount, and by which 15 frame the lamp is suspended; and the design consists in the configuration of the harp, as shown in the accompanying illustration.

The body *a* of the harp is of semicircular shape, curving upward at each side from the 20 center, each side terminating above in an inwardly-turned scroll-work. The suspending-arms *b* at each side terminate at their lower end in an outwardly-turned scroll-work, which is represented as tied to the inwardly-turned 25 scroll-shaped ends of the body *a*. Outside the body *a* branches *c* are represented as springing from the lower termination of the suspending-arms down outside the body *a*, following the line of the body, and ending in an outward 30 and upwardly turned scroll-work at each side at the bottom, the said two branches represented as connected at the bottom below the body by a bar, *d*, the said bar terminating at

its ends in scroll-work. The space between the body and the said bar below is filled with 35 the representation of rings, and centrally below the bar is a ring-shaped tip, as shown in the accompanying illustration.

The essential features of this design are the arms terminating in the scroll-work at their 40 lower ends, the semicircular-shaped body represented as terminating in scroll shape at the upper ends at the junetion with the arms, and the representation of the outside scroll-work branches at each side. 45

I claim—

The design for a harp for hanging lamps, consisting of the suspending-arms *b*, represented as terminating in scroll-work at their lower ends, the body *a*, of semicircular shape, its two 50 sides represented as terminating at their upper ends in inwardly-turned scroll-work and as hung to the scroll-work of the suspending-arms, with branches represented as springing from the scroll-work of the suspending-arms 55 and following down outside the body, terminating at their lower ends in outward and upwardly turned scroll-work, the said branches represented as connected by a bar below the body, as herein described, and shown in the 60 accompanying illustration.

ALBERT PATITZ.
